WRENCH HAVING A PIVOTED OUTER JAW

Bernard P. Kunz, Englewood, Colo.

Application November 5, 1949, Serial No. 125,672

1 Claim. (Cl. 81—99)

1

This invention relates to wrenches and more particularly the swinging jaw type which is automatically adjustable for use on different size work.

One of the objects of my invention is to produce an improved swinging jaw type of wrench which will be capable of efficiently gripping all sizes of work it is designed to receive between its jaw.

Another object is to produce a wrench of the type having a swinging jaw with right angular jaw faces and a cooperating fixed jaw with a circular jaw face which will have such a geometric relationship that efficient gripping action will be possible on all sizes of work which can be engaged, yet such action will not be so intense that an undesirable crushing action may be caused to occur by a low applied force.

A more specific object is to so construct a wrench of the type above referred to which is so designed that the angle between the pivotal axis of the swinging jaw, the center of the gripped work and the center of the curvature of the fixed jaw face will always be within predetermined limits for any size of round work that can be received between the jaws.

Other objects of my invention will become apparent from the following description taken in connection with the accompanying drawings in which:

Figure 1 is a side view of a head of a swinging jaw wrench embodying my invention, said figure showing the wrench gripping a size of round work approximately one-half maximum size for the wrench, and the geometric relationship existing under such conditions;

Figure 2 is a top view of the wrench; and

Figure 3 is another side view showing the wrench gripping approximately the largest possible round work and the geometric relationship existing under such conditions.

Referring to the drawings in detail, my improved wrench disclosed in the various figures comprises a handle member 10 and a swinging or pivoted jaw member 11. The handle member at one end has a hand gripping portion 12 (see Figure 2) and at its other end a jaw portion 13 to be referred to as the fixed jaw portion.

The swinging jaw member 11 is of general L-shaped form having a long leg portion 14 and a short leg portion 15. The free end of the long leg portion has a lateral extension 16 reduced in thickness and this extension portion fits into the end of a slot 17 at the jaw portion end of the handle member and is pivoted to this jaw portion end by a pin 18. At the free end of the long portion 14 of the swinging jaw member is a thumb engaging protuberance 19 to facilitate in opening up the swinging jaw member 11.

The longer leg portion 14 of the swinging jaw

2

member is provided with a jaw face 20 and the shorter leg portion is provided with a jaw face 21. These jaw faces are arranged to be preferably at right angles (90°) to each other although the relationship may be slightly varied within close limits. The two jaw faces are provided with teeth as shown for better gripping purposes.

The fixed jaw portion 13 on the end of the handle member and to which the swinging jaw member 11 is pivoted is provided with an outwardly curved jaw face 22, also provided with teeth for better gripping purposes. This curved jaw face 22 is constructed so that all of it will lie on a portion of a single circle, the center of which is at C and the radius of which is indicated at R. In other words, the face 22 has a single center of curvature and a single radius of curvature.

The three jaw faces 20, 21 and 22 all cooperate to hold various sizes of work such as those indicated at 23 in Figure 1 and at 24 in Figure 3. In order that the jaw faces may be automatically caused to engage with any work, a spring 25 is employed to bias the swinging jaw member toward the fixed jaw portion. This spring is positioned in the slot 17 of the handle portion with one end fixed to the handle by a pin 26 and the other end connected by a flexible ribbon member 27 to the swinging jaw in the manner shown in Figure 1.

To have a practical and efficiently operating wrench of the type described, that is a wrench having a swinging jaw member with two faces at right angles to each other and cooperating with a curved jaw portion faced on the end of a handle and having a single radius of curvature, I have discovered that certain geometric relationships must exist or are highly desirable. If most of these relationships are not present, it is not possible for the wrench to effectively grip all sizes of round work which can be placed between the three jaw faces of the wrench. Furthermore, if these relationships are not present, there is not available a substantial uniformity of gripping action for all sizes of round work. Without the relationships which constitute my invention, a swinging jaw wrench having the three kinds of jaw faces, that is, two right angular jaw faces and a curved jaw face having a single radius of curvature, a practical wrench would not be made. It would either slip on certain sizes of work or would have too great a crushing force on other sizes or would have other undesirable characteristics.

To have an efficiently operated wrench of the type referred to, there must exist a certain relationship between the axis of the pivot pin 18, indicated on the drawing as P, the center of the curved jaw face 22, indicated as C, the radius of said curved jaw face, indicated as R, and also

the relationship of the pivotal axis P of the pivot pin and the jaw face 20 of the swinging jaw member. There should also be a definite relationship of the position of the center C of the curved jaw face with respect to the longitudinal axis of the handle which passes through the axis P of the pivot pin.

In producing a wrench in accordance with my invention, the radius R of the curved jaw face on the end of the handle portion must be between 10 70 to 85% of the largest diameter of work which can be received between the various jaws when the swinging jaw is open to its fullest extent. The pivotal axis of the swinging jaw must also have a predetermined relationship with respect to the plane of the jaw face 20 of the swinging jaw member, said jaw face 20 being that face which is on the longest leg of the jaw member. This relation in the drawings is indicated by the letter D and is the shortest distance between 20 the pivotal axis P and the plane of the jaw face 20. I have discovered that this distance D should be approximately one-half the diameter of the largest round work which can be received between the jaws when the swinging jaw is in its maximum open position.

Another relationship which must be present for proper operation of the wrench is the relationship between the center C of the curved jaw face 22 and the pivotal axis P of the swinging jaw member. This relationship should be such that the largest angle which can exist between the two lines drawn from the center of any size work, which center is indicated on the drawings at W, to the center C and to the axis P (this angle is indicated as α on the drawings), must not exceed 30° and must not be less than 21°. In Figure 1 of the drawing the angle α is shown as the largest that can exist for the particular size wrench embodying my invention. This angle α is the one that is created for the size of work 23 indicated in Figure 1. If a larger size of work is operated upon by the wrench, then the angle α begins to decrease, as can be seen from Figure 3. This angle α for the larger diameter work 24 (somewhat smaller than the maximum that can be received between the jaws) being gripped by the wrench is considerably smaller than the angle α at its maximum as shown on Figure 1. If a smaller diameter of round work is gripped by the wrench, than that indicated as 23 in Figure 1, then the angle α will also decrease. If the relationship between the center C and the pivotal axis P should be such that a maximum angle α could exist which would be more than 30° or less than 21°, then the wrench would be inefficient in operation as a proper gripping action would not exist on work where this maximum angle was created. It would not be possible for the wrench to properly grip round work so that slippage would not be present. When the maximum angle α is greater than 30°, slippage occurs and when the maximum angle is below 21°, the range of sizes of round work which the wrench can accommodate will be too small for practical purposes. Also an undesirable crushing effect will exist for low forces acting on the handle of the wrench. In other words, the wrench if operating on light pipe or tubing could easily crush this work by the cam action present.

When the proper relationship between the center C and the axis P exists, there will also be a definite relationship between a line drawn between these two points and that longitudinal axis

of the handle of the wrench which passes through the pivot point P. In the drawings this longitudinal axis is indicated by the line PL and the angular relationship of this line to the line drawn between the axis P and the center C should be between 40° and 65°. In other words, it is not only necessary that C be located a predetermined distance from P but it should have a certain position with respect to the longitudinal center line PL.

In the wrench disclosed as embodying my invention there are embodied several new discoveries which I have found to be essential and desirable in constructing an efficient and practical wrench particularly a wrench of the swinging jaw type in which the swinging jaw has right angular jaw faces and the fixed cooperating jaw has an outward curved face of a single radius of curvature. These discoveries which involve certain relationships as described need not all be embodied in a single wrench to make it workable although I have discovered that when all embodied in the manner disclosed there is produced the best wrench possible. However, being aware of the possibilities of using certain of my discoveries in a manner somewhat different than that disclosed in the same or similar types of wrenches to obtain the same results, I desire it to be understood that my invention is not to be limited in scope except as set forth in the appended claim.

What is claimed is:

In a wrench of the class described, a handle member having a jaw portion provided with an outwardly curved jaw face having a single center of curvature, and a swinging jaw member having an inwardly directed extension pivoted to the handle member and provided with jaw faces each lying in a single plane and said faces being at right angles to each other whereby round work can be received and gripped between all three jaw faces, the pivotal axis of the swinging jaw member being so related to the right angular jaw faces and the position of the center of curvature of the curved jaw face that the angle which can exist between a line drawn from the center of any size round work receivable between the jaw faces to the pivotal axis and another line drawn from said center to the single center of curvature of the engaged curved jaw face will not be greater than thirty degrees or less than twenty-one degrees, the pivotal axis of the swinging jaw member being so related to the right angular jaw faces and also to the curved jaw face that the largest diameter of round work that can be received between the jaw faces will be approximately twice the shortest distance between the pivotal axis and the plane in which lies that jaw face of the swinging jaw member which is closest to the pivotal axis.
